UNITED STATES PATENT OFFICE.

CHRISTOPHER TREANOR, OF OAKLAND, CALIFORNIA.

STREET-INDICATOR.

1,354,149.

Specification of Letters Patent. Patented Sept. 28, 1920.

Application filed May 5, 1920. Serial No. 379,053.

To all whom it may concern:

Be it known that I, CHRISTOPHER TREANOR, a citizen of the United States, residing at Oakland, in the county of Alameda 5 and State of California, have invented new and useful Improvements in Street-Indicators, of which the following is a specification.

My invention relates to street indicators 10 particularly adapted for use by street car companies, for indicating points along a car's route, such as streets or stations, to be reached by the car at certain pre-arranged periods of time, and in which a 15 watch or like instrument for measuring time is used co-operatively with a movable chart.

An object of the present invention is to 20 provide a street indicator adapted to be installed upon a street railway car, or be carried upon the person of the operator of the car, embodying a case in which is disposed a chart ribbon windable from one reel onto another. The ribbon being spaced into sections, each section provided with a circular 25 opening having upon its margin characters representing the names of the streets or stations along the car's route, co-operating with a watch or like time-piece carried in the case. The arrangement being such that the 30 hands of the watch will indicate upon the chart the name of the street or station that it may be desired to be reached by the car at a given time.

Other objects of the invention will appear 35 as the description proceeds.

It is intended that changes in the precise embodiment of the invention as shown and described may be made within the scope of what is claimed, without departing from 40 the spirit of the invention.

In the accompanying drawings—

Figure 1 is a front elevation of the indicator in its preferred form, showing a watch disposed in the case.

Fig. 2 is a view on line *a—a*, Fig. 1, with a view of the watch as looking down upon the stem.

Fig. 3 is a side view of a portion of the chart ribbon, unwound.

Fig. 4 is a front elevation of the device, with portions thereof cut away.

Fig. 5 is a sectional view on line *b—b*, Fig. 1.

Fig. 6 is a top view of the case.

Referring to the drawings in detail, 55 throughout which like reference numerals indicate like parts,—

The numeral 1 designates a case embodying a front wall 2 provided with a circular opening 3, a rear wall 4, a top 5, and a bottom 6.

The rear wall 4 is indented so as to form an interior concaved portion 7 conforming with the contour of the back of a watch 8, which is provided with a common circular 65 clock dial 9, the margin of which being divided into twelve equal parts or spaces indicated on the dial by the numerals 1 to 12 inclusive, and an hour hand 10 and minute hand 11. One revolution of the hour hand 10 around the dial 9 representing twelve 70 hours of time, and one revolution of the minute hand 11 about the face of the dial representing one hour of time.

The watch 8 is adapted to be disposed in 75 the case 1 and arranged therein in such a manner that the dial 9 will be opposite the opening 3 and its stem will project upwardly through an opening 12 in the top wall 5 of the case.

13, 13, designate a pair of reels carried in the case 1 and disposed one on each side of the watch 8. Said reels provided with upper reduced ends 14, rotatable in openings 16 in the top wall 5, and reduced ends 17 rotatable in openings 18 in the bottom wall 6 of the case 1.

The free ends of the reduced upper ends 14 are provided with bosses 19 adapted to be engaged by the operator for rotating the 90 reels in either direction.

To the reels 13, 13, are secured the ends of a chart ribbon 20, which ribbon is considerably longer than the case 1, and is windable from one reel onto another by turning 95 the bosses to rotate the reels in the proper direction.

The ribbon 20 is provided with a number of circular openings, upon the margin of each of said openings is indicated the names or titles of the streets and stations along the car's route that it is desired to have the car arrive at, at a certain period of time. A portion of the ribbon and openings only being shown in the drawings.

In Fig. 3 the openings shown are indi-

cated by the reference numerals 21, 22 and 23. The openings shown in Figs. 1 and 4 corresponding in marginal characters with the opening 23 in Fig. 3.

5 The ribbon 20 may be of any desired length and may be provided with any suitable number of aforesaid openings.

In winding the ribbon from one reel onto the other, it will be caused to move across the dial 9, between the watch 8 and the front wall 2 of the case 1.

In Fig. 1 of the drawings, the indicator is shown with the ribbon 20 moved across the face of the watch into a position so that 15 the opening corresponding with the opening 23 in Fig. 3 is brought into position to register with dial 9. In this position the device is shown to indicate that the car is intended to depart from the car barn at 20 twelve o'clock and to arrive at 24th street at fifteen minutes after twelve, at 48th street at thirty minutes after twelve, at 72nd street at forty-five minutes after twelve, and at the farthest end or terminal 25 of the car's run at 1 o'clock. (The terminal of the car's run being indicated on the margin of the opening 23 ^{"car barn"} which also indicates the starting point of the car.)

30 Upon the return trip of the car over the same route as when out-going, the operator would rotate the proper reel to move the ribbon 20 from left to right across the face of the clock until the opening 22 came opposite the dial 9, and assuming that the car started upon its return trip immediately upon its arrival at the end of its route, and that it traveled at the same rate of speed 35 on its return trip as when out-going, then 40 at fifteen minutes past the hour the minute hand 11 would point to 72nd street, at thirty minutes after the hour to 48th street, at forty-five minutes after the hour to 24th street, and fifteen minutes thereafter to car 45 barn, which would be the end of the return trip.

In Fig. 3 of the drawings, the opening 21 when moved into position to register with the dial 9, would indicate that the car was 50 intended to leave the car barn at ten minutes after the hour, and arrive at 24th street at twenty-five minutes after the hour.

In Fig. 4 the minute hand 11 indicates fifteen minutes after twelve on the dial of 55 the clock, and 24th street on the margin of the opening 23, indicating that the car should arrive at 24th street at fifteen minutes after departing from the car barn.

It is to be understood that any desired 60 number of streets, stations, or the like, may be indicated upon the margin of the openings in the ribbon, the names of said streets or stations to be indicated on the margin of the opening to register with the 65 time indications on the clock's dial to cor-

respond with the period of time that it is desired to reach said streets or station.

Having described my invention, I claim:

1. In a street indicator of the class described, the combination with a case having an opening in its front wall and a clock carried in the case with its dial in axial alinement with said opening, of a pair of vertically disposed reels carried inside the case and disposed one on each side of the clock, 70 and a ribbon disposed between the dial of the clock and said front wall, the ribbon being windable from one of said reels onto the other thereof and provided with a plurality of circular openings extending 75 through from one side to the other, and means for rotating said reels for moving said ribbon across said dial so that one of said last named openings may be brought into axial alinement with said dial and said 80 first named opening.

2. A device of the character described, comprising a case having a slot in its upper end through which is adapted to project the winding member of a time-piece, a circular 90 opening in the front wall of the case, said opening in axial alinement with the dial of said time-piece, a vertically disposed spool rotatably fitted in each end of the case, a flexible ribbon having its free ends secured 95 to said spools and so arranged relative thereto so that the surplus of the ribbon may be wound from one of the spools onto the other, said ribbon provided with a plurality of circular openings spaced apart along the 100 face of the ribbon, each of said openings provided around its margin with characters indicative of stops along the car's route, said characters adapted to be co-readable with the hands of the time-piece. 105

3. The combination with a watch-like time-piece having a winding-stem projecting upwardly from one edge, of a case for inclosing said time-piece, the case having an opening in its upper end through which is 110 adapted to project said winding stem, a circular opening in the front wall of the case in axial alinement with the axis of the dial of said time-piece, a pair of rotatable spools vertically disposed inside the case one on 115 each side of the time-piece, a projection on the upper end of each of said spools extending out through the upper end of the case and adapted to be engaged by the operator for rotating the spools, a comparatively 120 long flexible ribbon, one end of said ribbon secured to one of the spools and the other end thereof secured to the other of the spools, an intermediate portion of the ribbon windable from one of said spools onto 125 the other thereof, said ribbon provided with a plurality of circular openings, said openings spaced equal distances apart along the ribbon and each provided around its margin with car-stop indicating characters readable 130

with the time indicating characters on the dial of said time-piece, the arrangement of ribbon being such that by rotating one of said spools in the proper direction the ribbon may be caused to move horizontally across the face of the time-piece so that either one of said last named openings may

be brought into axial alinement with the axis of the dial of the time-piece and the front opening the case.

10

In evidence that the foregoing is my own, I hereunto sign my name this 10th day of April, 1920.

CHRISTOPHER TREANOR.
